The ornamental design for a fin for use in a fin and tube heat exchanger in an air conditioner, as shown and described.

DESCRIPTION

FIG. 1 is a front elevation view of a fin for use in a fin and tube heat exchanger in an air conditioner, showing our new design;

FIG. 2 is a rear elevation view thereof;

FIG. 3 is a left side elevation view thereof;

FIG. 4 is a right side elevation view thereof;

FIG. 5 is a top plan view thereof, the bottom being a mirror image of that shown; and,

FIG. 6 is a cross-sectional view thereof taken on line 6—6 of FIG. 1.

FIG.1

FIG. 3

FIG. 4

FIG. 2

FIG. 5

FIG. 6
